UNITED STATES PATENT OFFICE.

JULIUS H. SCHLAFLY, OF CANTON, OHIO, ASSIGNOR TO THE CANTON CULVERT COMPANY, OF CANTON, OHIO, A CORPORATION OF OHIO.

CULVERT.

1,077,232.

Specification of Letters Patent.

Patented Oct. 28, 1913.

Application filed March 6, 1909. Serial No. 481,735.

To all whom it may concern:

Be it known that I, JULIUS H. SCHLAFLY, a citizen of the United States, residing at Canton, in the county of Stark and State of Ohio, have invented a new and useful Culvert, of which the following is a specification.

My invention relates to improvements in culverts of the sectional, nestable class constructed of sheet metal and adapted to be connected together to form a complete pipe or culvert, and the invention particularly resides in the means for connecting the said sections together in the manner stated.

The object of the invention is to provide a simple, cheaply constructed, strong and durable culvert adapted to be shipped or transported in a nested condition and to be readily set up, connected together, and put in place with the aid of the simplest tools, the operation of connecting the sections being so easily performed as not to require the services of a skilled workman.

I attain this object, together with other objects readily apparent to those skilled in the art, by the construction illustrated in the accompanying drawing, in which—

Figure 1 illustrates a culvert composed of complementary sections arranged as top and bottom sections to form a culvert, one of said sections being removed to further disclose the construction. Fig. 2 is a perspective view of two of the lower sections so arranged as to illustrate the manner in which the ends of longitudinally adjacent bottom sections overlap at their meeting edges, where that form of culvert is used in which the compound flanges terminate short of one end of the section. Fig. 3 is a transverse sectional view through upper and lower sections properly joined. Fig. 4 is a perspective view of two of the lower sections arranged to illustrate that form of the culvert in which recesses are pressed outwardly in the compound flanges. Fig. 5 is a perspective view of the two sections illustrated in Fig. 4 properly arranged to receive the top complementary sections. Fig. 6 is a perspective view of two bottom sections illustrating that form in which recesses are pressed inwardly in the compound flanges.

Throughout the several views similar numerals of reference indicate similar parts.

The sections forming the culvert may be either corrugated or plain, the corrugated

form being preferred because of its greater strength. In the drawing the numeral 1 indicates one of the upper complementary sections. These sections are substantially semi-cylindrical and may be provided with circumferential corrugations, as shown. Along the side edges of each top section is provided the integral, laterally extending flange 2 which may be either plain or corrugated, the plain flange being preferred because of the fact that by its use a neater joint may be made. The drawing discloses the construction in which the plain flange is employed, the circumferential corrugations terminating at the line where the metal is bent laterally to form the flange.

The lower complementary sections 3 are substantially semi-cylindrical and are provided with integral, compound flanges consisting of a laterally extending flange 4 and the integral flange 5 arranged at right angles to the flange 4, the flange 5 being adapted to be bent or folded down upon the flange 4 for the purpose of engaging and holding in place the flanges 2 of the complementary top section as hereinafter more fully explained.

The compound flanges on the lower sections may extend along the side edges from end to end of each section if desired. It will be understood, however, that inlapping the ends of longitudinally adjacent lower sections the compound flanges will also be lapped, and in some instances this lapping of the flanges with the incidental doubling of the metal and unevenness may be considered objectionable. To avoid this objectionable feature I provide the method of construction illustrated in Figs. 2, 4 and 6. In the construction illustrated in Fig. 2 the compound flanges at one end of each lower section are cut away or made to terminate short of the end of the section, as illustrated at 6. This will permit the flanges of longitudinally adjacent lower sections to abut end to end instead of overlapping each other although the ends of the culvert sections exclusive of the flanges will over-lap each other as usual. In Fig. 4 the compound flanges at one end of one section are provided with the recessed portions 7, the flange 4 being pressed downwardly substantially the thickness of the sheet metal of which the sections are constructed and the flange 5 being pressed outwardly the same

distance. The flanges of the longitudinally adjacent lower section will then lie within the said recesses when the ends of the sections are over-lapped, producing the arrangement illustrated in Fig. 5 and providing a smooth and even flange 4 extending throughout the over-lapping sections and permitting the flange 2 of the complementary section to lie flat against the flanges 4 of the over-lapping lower sections. The recess 7 also permits the flanges 5 of the two lower sections to be so aligned that when the flanges 5 are folded or bent down upon the flange 2 of a complementary section a neater joint or seam will be produced.

In Fig. 6 the recesses 8 in the flanges 4 and 5 are pressed inwardly instead of outwardly, the arrangement producing to a certain extent, the reverse arrangement from that shown in Figs. 4 and 5. The recesses 8 do not produce quite so smooth and even a joint or seam as the recesses 7, but by means of their use the over-lapping compound flanges are caused to make a neater joint or fold at their over-lapping portions, which is the point in the seam or joint requiring the greatest strength and most careful construction.

It should be stated that the flanges 2 are of approximately the same width as the flanges 4, as will be readily understood from an inspection of Fig. 3. It will be noted also, that if the sections are provided with circumferential corrugations the end corrugations of longitudinally adjacent sections will be adapted to engage each other where the said sections are over-lapped, thus producing a strong and substantial joint.

In arranging the complementary sections it is well to lap the meeting ends of longitudinally adjacent sections at a point intermediate the ends of the complementary section, thus breaking the joints and securing structural advantages.

The various sections having been provided as hereinbefore described, the method of connecting said sections together to form a culvert is as follows: An appropriate number of lower sections are arranged with the meeting ends of longitudinally adjacent sections over-lapping; the compound flanges upon said lower sections will then form a continuous ledge upon which the lateral flanges of the top or complementary sections 55 may rest. The top sections are then arranged in a longitudinal series upon the lower sections, the meeting ends of adjacent top sections being over-lapped substantially as in the case of the lower sections and the 60 various sections being so arranged as to break joints, as hereinbefore described. It is then only necessary to use a hammer or other suitable tool to bend over or fold down the flanges 5 upon the flanges 2, as 65 illustrated in Fig. 3, thus producing a firm

and substantial connection between the sections.

While I have shown and described upper and lower sections, the upper sections provided with simple flanges and the lower sections provided with compound flanges, it is evident that the sections might be formed so that each section would be provided with one simple flange and one compound flange, so that a culvert could be produced from any two of such sections which might be in stock. It should also be noted that a culvert might be constructed with similar means of fastening the seam where there is only one seam to the complete culvert, the same not being made in sections and likewise more than two sections may be employed if it is found practical or expedient to do so.

While I have described the method of connecting the sections as above I do not desire to be limited to this method. It is evident that the flanges 5 might be folded down practically into the position illustrated in Fig. 3 and that the flanges of the sections 1 might be slipped into position between the flanges 4 and 5 of the complementary sections by starting the said flanges 2 into the grooves between the flanges 4 and 5 at the end of the section and sliding the sections relatively to each other until the appropriate relative position has been attained.

I claim:

1. In a culvert of the class described, lower sections arranged in a longitudinal series, the meeting edges of longitudinally adjacent sections in the series over-lapping, upper complementary sections arranged in a longitudinal series, the meeting edges of longitudinally adjacent sections in the upper series over-lapping, said upper sections provided with integral, laterally extending flanges and said lower sections provided with integral, compound flanges including portions adapted to support the flanges on the upper sections, and other integral portions adapted to be folded over the flanges on said upper sections, for the purpose of connecting the complementary sections of the upper and lower series.

2. In a culvert of the class described, lower, circumferentially corrugated sections arranged in a longitudinal series, the end edges of longitudinally adjacent sections over-lapping, upper circumferentially corrugated complementary sections arranged in a longitudinal series, the end edges of longitudinally adjacent sections of the upper series over-lapping, said upper sections provided with integral, laterally extending flanges, said lower sections provided with integral, compound flanges including portions adapted to engage the flanges on the upper sections, and other integral portions adapted to be folded over the flanges on said upper sections, for the purpose of con-

necting the sections of the upper and lower series to each other.

3. A sheet metal culvert composed of complementary, circumferentially corrugated sections arranged in upper and lower longitudinal series, the end edges of longitudinally adjacent sections in both series overlapping, the side edges of said sections forming a longitudinal seam, the side edges of said upper sections provided with laterally extending flanges, and the side edges of said lower sections provided with compound flanges, the first mentioned flanges resting upon portions of the compound flanges, and other portions of the compound flanges folded over the said first mentioned flanges.

4. A sheet metal culvert composed of corrugated sections arranged in upper and lower longitudinal series, the end edges of longitudinally adjacent sections in both series overlapping, the side edges of said sections adapted to form a longitudinal seam, the said side edges of said upper sections provided with laterally extending flanges, the side edges of said lower sections provided with compound flanges, the first mentioned flanges being adapted to rest upon portions of the compound flanges and other portions of the compound flanges adapted to be folded over the said first mentioned flanges, for the purpose of connecting the said edges to each other.

5. A sheet metal culvert composed of an upper and lower longitudinal series of circumferentially corrugated, endwise over-lapping sections, the sections of the upper series provided with lateral, simple flanges, the sections composing the lower series provided with compound, lateral flanges, and portions of said flanges adapted to be folded over said simple flanges, for the purpose of holding the complementary sections together.

6. A culvert section provided with edges and integral, compound flanges arranged upon said edges, said flanges composed of two portions, the one portion adapted to be folded upon the other, and said compound flanges provided with recesses for the accommodation of the over-lapping portions of the compound flanges of an endwise overlapping longitudinally adjacent culvert section.

7. A semi-cylindrical culvert section provided with integral, compound flanges along its side edges, said flanges consisting of two members adapted to be folded together for the purpose of including between them the flange of a complementary section, and said first mentioned section provided with re-

cesses in the compound flanges for the reception of the over-lapping portions of the compound flanges of a longitudinally adjacent endwise over-lapping similar section.

8. In a culvert of the class described, sections arranged in a longitudinal series, the meeting edges of longitudinal adjacent sections in the series over-lapping, said sections provided with integral, compound flanges, and said flanges at one end of each section being provided with recesses for the reception of the over-lapping flanges of the longitudinally adjacent section.

9. In a culvert of the class described, lower sections arranged in a longitudinal series, the meeting edges of longitudinally adjacent sections in the series over-lapped, upper complementary sections arranged in a longitudinal series, the meeting edges of longitudinal adjacent sections in the upper series over-lapping, said upper sections provided with integral, laterally extending flanges and said lower sections provided with integral, compound flanges including portions adapted to support the flanges on the upper sections, and other integral portions adapted to be folded over the flanges on said upper sections, said compound flanges at one of the ends of each section being also provided with recesses for the reception of the over-lapping compound flanges of the longitudinally adjacent section.

10. A sheet metal culvert composed of complementary, circumferentially corrugated sections arranged in upper and lower longitudinal series, the end edges of longitudinally adjacent sections in both series over-lapping, the side edges of said sections forming a longitudinal seam, the side edges of said upper sections provided with laterally extending flanges and the side edges of said lower sections provided with compound flanges, said compound flanges at one end of each lower section provided with recesses for the reception of the over-lapping flanges of the longitudinally adjacent lower section, the flanges of the sections in the upper series resting upon portions of the compound flanges of the lower series, and other portions of said compound flanges folded over the flanges of the upper sections.

In testimony that I claim the above, I have hereunto subscribed my name in the presence of two witnesses.

JULIUS H. SCHLAFLY.
